UNITED STATES PATENT OFFICE

2,519,116

DEFORMABLE PACKER

Wilfred S. Crake, Houston, Tex., assignor to Shell Development Company, San Francisco, Calif., a corporation of Delaware

Application December 28, 1948, Serial No. 67,707

4 Claims. (Cl. 166—10)

1

This invention relates to new and useful improvements in packing elements and pertains more particularly to casing-packers for well producing installations as, for example, pumping systems that are commonly used in oil wells.

In an oil well lined with a casing and having an inner string of pipe or tubing extending within said well casing to remove the well fluid therefrom, it is often desirable to pack or seal off the annular space between the tubing string and the outer casing. Many oil and gas fields have more than one producing zone and oil or gas may be obtained from two zones simultaneously by employing a single well comprising two concentric production strings. A suitable packer is carried on the inner string of pipe or tubing and is arranged to sealingly engage the well casing so that production from the lower zone is produced through the inner tubing string while the production from the upper zone flows through the annular space between the well casing and the inner tubing string. Packers that are generally used in an installation of the above-described type to seal the annular space between the casing and the tubing string are normally made of a flexible or resilient material and are set by manipulation of the tubing string.

An object of this invention is to provide a simple, efficient and commercially practical method for permanently packing off the annular space in a well between the well casing and an inner production tubing positioned therein whereby two spaced or separate zones may be simultaneously produced through said casing and said tubing.

Another object of the present invention is to provide a permanently set casing-packer adapted to be carried by a tubing string inserted in a well casing and explosively expanded against the inner wall of the well casing, whereby a fluid-tight joint or seal is formed between said tubing string and said well casing.

A further object of this invention is to provide a metallic packer adapted to be permanently set in a fluidtight manner, and means for setting said packer by an explosive charge.

Other objects and advantages of the present invention will become apparent from the following description taken with reference to the drawing, wherein:

Figures 1 and 2 are longitudinal views, partly in cross section of the present packer and setting means positioned within a well.

Figure 3 is a longitudinal cross-sectional view of the present packer after it has been set in a well casing.

2

Referring to the drawing, the packer 10 of the present invention is shown as forming part of a tubing string comprising sections or lengths of tubing 11 and 12 threadedly connected to the packer 10 at 13 and 14, respectively. The packer 10 is formed of an easily deformable metallic tubular member having a bore 15 adjacent the threaded ends 13 and 14 of said packer, said bore being equal in diameter to that of the adjacent pipe sections 11 and 12. At substantially the center of the packer, the axial bore 15 is enlarged or recessed forming an annular groove 16. Preferably, the inner wall of the packer 10 may have formed therein a second annular groove 17 adjacent the upper threaded end 13.

The wall 18 of the packer is preferably twice as thick as the wall of the adjacent tubing section 11 so that the wall 20 of the packer, adjacent the annular groove 16, may be as thick as the tubing wall 19 and preferably twice as thick. Thus the enlarged portions of the wall 18 of the packer form constrictions within the packer 10 in which a packer setting means may be positioned. The height of the annular groove 16 is at least equal to the diameter of the axial bore 15 of said packer 10. Formed on the outer surface of recessed wall 20 is one or more annular grooves 21 adapted to receive and hold an annular sealing element 22 which may be of any suitable material as, for example, rubber, synthetic rubber, paint, a soft pliable metal such as lead, or any suitable plastic material. Paints or plastic materials used as sealing elements in oil well packers are preferably of a type unaffected by the oil or other materials encountered in an oil well and of a type that hardens and sets against the wall of a well casing 23 to prevent leakage of gas or liquids vertically past any scored places in the casing wall after the packer has been set.

The packer 10 may be made of any suitable metal (or plastic) adapted to be distended outwardly against the well casing 23 when subjected to an internal force such as one created when an explosive charge is ignited, said packer becoming permanently formed in its distended shape to pack off the annular space between a tubing string and the well casing. At the same time the bore 15 of the packer remains open and in communication with the sections of tubing string 11 and 12 above and below. Preferably the packer is made of a dead soft low carbon annealed steel or annealed extruded aluminum. A higher carbon steel may also be used when the recessed wall portion 20 is annealed dead soft. The packer may also be made of copper or any

other metal or alloy thereof that is ductile, malleable or easily deformable.

The present metallic packer 10 is set against the well casing, 23, by positioning and detonating an explosive charge in the bore of said packer opposite the recessed wall portion 20 thereof. A preferred embodiment of the packer setting means is shown in Figure 1 as comprising an elongated cylindrical metal plug or bar 24 of a diameter slightly smaller than the bore of the tubing string 11 or packer 10 thus permitting the bar to freely slide down said tubing string and be positioned in said packer 10. One portion of the bar 24 is reduced in diameter forming an annular groove 25 about said bar and a mandrel 32 about which an explosive charge 26 may be wrapped. The explosive charge 26 for expanding the packer 10 is carried in said annular groove 25, said explosive charge being either wrapped or formed about said bar in a manner such that the diameter of the explosive charge 26 is no greater than that of the carrier bar 24. Thus, when the bar 24 and explosive 26 are positioned within the axial bore 15 of said packer 10, the mandrel 32 and the grooved or recessed wall 20 form the inner and outer walls of a closed annular chamber.

The corners 34 of the annular groove 25 are preferably rounded to obviate distortion of the bar member 24 by forces exerted by the explosive charge. In a like manner the corners 35 of the annular groove 16 in the packer 10 are preferably rounded to eliminate possible cracking of the wall 20. Since the bar member 24 above and below the mandrel section 32 are of the same diameter, an exploding charge exerts the same pressure against the bar at both ends of said mandrel 32. Hence the bar 24 has no tendency to move vertically at the same time of the discharge.

Formed or drilled in the bar member 24 is a suitable hole or recess 27 adapted to receive a detonator (not shown) and a passageway 28 containing insulated electrical conduit means 29 for firing the detonator and explosive charge 26. If a detonator is not used to set off the explosive charge, the electrical conduit means may be run directly from passageway 28 through recess 27 to the charge 26. Preferably, the electrical conduit means is of the current-conducting and load-bearing type whereby the explosive charge may be lowered through the tubing string 11 in the well.

Suitable means are affixed to said bar member 24 for fixedly positioning the explosive charge carried thereby opposite the recessed wall portion 20 of said packer 10. In the embodiment shown the positioning means comprise a plurality of spring elements 30 fixedly secured to and radially extending from a reduced upper portion 31 of said bar member 24. The springs 30 are adapted to expand into the annular groove 16 of the packer 10 and prevent further downward travel of the bar member 24. In this embodiment the lower end 33 of the bar member 24 forms a sinker bar of sufficient weight to pull the bar and attached cable 29 down the well and into position in the packer 10. It is evident that the sinker bar could alternatively be positioned above the spring elements 30 for pushing the springs 30, mandrel 32 and explosive charge 26 into place.

The bar member 24 is normally made of steel in order to withstand the detonation of the explosive charge without being shattered or deformed. Preferably, the diameter of the bar 24

is substantially equal to the diameter of the axial bore of the packer thus forming means for closing the axial bore 15 of said packer 10 and restricting the flow of the expanding gases generated by the explosion when the charge 26 is detonated. Thus, the major portion of the explosive forces is directed radially to expand the packer wall 20. It is realized that when a packer 10 of an extremely soft material is employed it may be desirable to use an explosive carrying bar 24 of reduced diameter thus allowing some of an explosive force to be dissipated upwards and downwards in the tubing string 11 and 12 to prevent the soft packer material from being shattered.

Preferably, however, the forces generated by an exploding charge are controlled by a proper selection of the size and type of explosive charge used. Thus, an explosive is selected that detonates with a force sharp enough to expand the packer 10 without shattering it. Since various explosives of this type are well known in the field of military and commercial explosives, they will not be further described here.

In operation, a metallic packer 10 of the above-described type is coupled between two sections 11 and 12 of a tubing string 36 and lowered into a well casing 23 as shown in Figure 3. If a very soft metal packer 10 is employed, and the length and weight of the tubing string 12 depending below the packer 10 is substantial, it may be desirable to mount a tubing hanger, diagrammatically represented at 37, on the tubing below said packer 10 for anchoring the tubing to the casing 23, as shown. In such a case the anchor 37 is actuated by manipulation of the tubing string 36 before the packer 10 is set. The structure and operation of tubing anchors, forming no part of this invention and being well known in the art of oil well equipment, will not be described here.

The explosive-carrying bar 24 is then inserted in the top of the tubing string 36 and lowered by means of the cable 29 which passes over a pulley 38 and is unwound from suitable winch means 39. As the depth of the packer 10 is generally known by the number of lengths of tubing 26 that were connected together and run into the well, the proper length of cable 29 is unwound from the winch 39 until the bar 24 is positioned in the packer 10. If the location of the packer 10 is unknown, a sensitive weight indicator located at the surface (not shown) may be connected to or in contact with the cable 29, said indicator being actuated each time that the springs or feeler wires 30 pass a groove or joint in the tubing string 36. In either case the bar 24 may be lowered until the springs are in the annular groove 16 of the packer 10 in order to accurately position the bar. The bar 24 is then raised slightly until the springs 30 seat in the annular groove 16 at which time the explosive charge is exactly opposite the recessed wall 20 of the packer 10.

With the bar 24 positioned in the packer 10, an electric current is sent down the cable 29 from any suitable power source at the surface to detonate the explosive charge 26. The force of the explosion distends the recessed wall 20 of the packer 10 into substantially fluidtight permanent contact with the well casing 23 as shown in Figure 3 after the bar 24 has been hoisted by the cable 29 up the tubing 36. The annular sealing element 22 carried by said packer 10 is compressed against the casing 23 to form a

fluidtight seal between the packer 10 and the casing 23.

If desired, the upper threaded end 13 of the packer 10 may be a left hand thread so that the attached tubing section 11 could be disconnected by rotating the tubing string to the right from the surface. The packer 10, being made of relatively soft metal, could then be drilled out.

I claim as my invention:

1. Apparatus for packing off the annular space between an inner and an outer tubular string in a well, comprising, in combination, a cylindrical packer member made of deformable material having an axial bore therethrough, means at either end of said cylindrical packer for connecting said packer into the inner tubular string, said axial bore having constrictions throughout two spaced portions thereof, a cylindrical mandrel having two axially spaced portions of enlarged diameter, the diameter of said enlarged portions and the spacing therebetween being respectively equal to those of the constricted portions of the axial bore, an annular explosive charge disposed around said mandrel between the enlarged portions thereof, means for positioning said mandrel within the bore of said packer with the enlarged portions of the mandrel in register with the constricted portions of said bore, said means comprising an electric conductor cable attached to said mandrel, and means for exploding said charge by an electric impulse transmitted through said cable, said means comprising igniter passage means in said mandrel in communication between said conductor cable and said charge.

2. Apparatus for packing off the annular space between an inner and an outer tubular string in a well, comprising, in combination, a cylindrical packer member made of non-resilient deformable material having an axial bore therethrough, an annular groove formed in the outer wall of said cylindrical packer intermediate the ends thereof, sealing means carried in said annular groove, means at either end of said cylindrical packer for connecting said packer into the inner tubular string, said axial bore having annular constrictions throughout two spaced portions thereof, a cylindrical mandrel having two axially spaced portions of enlarged diameter, the diameter of said enlarged portions and the spacing therebetween being substantially equal respectively to those of the constricted portions of the axial bore, an annular explosive charge disposed around said mandrel between the enlarged portions thereof, means for positioning said mandrel within the bore of said packer with the enlarged portions of the mandrel in register with the constricted portions of said bore, said means comprising an electric conductor cable attached to said mandrel, and means for exploding said charge by an electric impulse transmitted through said cable, whereby said wall of said cylindrical packer member between said annular constrictions is expanded radially into fixed fluidtight engagement with said outer tubular string.

3. Apparatus for packing off the annular space

between an inner and an outer tubular string in a well, comprising, in combination, a cylindrical packer member made of a malleable metal having an axial bore therethrough, an annular groove formed in the outer wall of said cylindrical packer intermediate the ends thereof, sealing means carried in said annular groove thread means at either end of said cylindrical packer for connecting said packer into the inner tubular string, said axial bore having constrictions throughout two spaced portions thereof, a cylindrical mandrel having two axially spaced portions of enlarged diameter, the diameter of said enlarged portions and the spacing therebetween being respectively equal to those of the constricted portions of the axial bore, an annular explosive charge disposed around said mandrel between the enlarged portions thereof, electric conductor cable means attached to said mandrel for lowering said mandrel through said inner tubular string, spring means for positioning said mandrel within the bore of said packer with the enlarged portions of the mandrel in register with the constricted portions of said bore, and means for exploding said charge by an electric impulse transmitted through said cable, said means comprising igniter means in said mandrel in communication between said conductor cable and said charge.

30 4. Apparatus for packing off the annular space between an inner and an outer tubular string in a well, comprising, in combination, a non-resilient deformable metallic tubular packer having an axial bore therethrough, an annular recess in the inner wall of said tubular packer intermediate the ends thereof, means for securing the open ends of said tubular packer into said inner tubular string, cylindrical mandrel means adapted to be slidingly passed through said inner string and said tubular packer for substantially closing the ends of said tubular packer, said mandrel means having an annular groove in its outer surface with the diameter of said mandrel means being substantially equal to that of the axial bore 45 whereby a substantially pressure-tight annular chamber is formed between the mandrel means and the recessed inner wall portions of said tubular packer, an explosive charge carried in the annular groove of said mandrel means, means for removably positioning said mandrel means within the bore of said packer with the explosive charge carried by said mandrel in register with the recessed wall portion of said packer, said means comprising an electrical conductor cable 55 attached to said mandrel, and means interposed between said cable and said charge for exploding said charge by an electric impulse transmitted through said cable, whereby the recessed wall portion of the tubular packer is expanded into 60 rigid fluid-tight contact with said outer tubular string.
